PORTABLE SEESAW

Ethan Heinly, Virginville, Pa.

Application October 19, 1933, Serial No. 694,327

8 Claims. (Cl. 272—54)

This invention relates to a portable seesaw designed primarily for playgrounds, but it is to be understood that the seesaw is adapted for any location for which it may be found applicable, and the invention has for its object to provide, in a manner as hereinafter set forth, a structure of the class referred to including a pair of end carriers to which are anchored the seats for the individuals using the device, and with the said carriers so coupled with the rockable or teetering structure of the seesaw to provide for the said seats to be at all times in supporting position parallel to the surface upon which the device is mounted during rocking or teetering.

A further object of the invention is to provide, in a manner as hereinafter set forth, a seesaw including a skeleton rocking or teetering structure having the joints between the elements thereof, as well as the pivots therefor being unusually strong, compact and durable, and with the pivots capable of being readily lubricated when desired.

A further object of the invention is to provide, in a manner as hereinafter set forth, a seesaw including a rocking or teetering structure including superposed central pivots and end pivots for said structure, bearing sleeves associating with and encompassing each pivot to reduce the wear upon the latter whereby its life is materially increased, and with the bearing sleeves assembled in a manner with respect to their associated pivots to permit, when desired to remove and replace the sleeves without completely dismantling the pivots relative to said structure.

A further object of the invention is to provide, in a manner as hereinafter set forth, a portable seesaw including a pull bar forming an element of the rocking or teetering structure of the device, a handle bar in proximity to each end of the pull bar, seat carriers having said structure pivoted therewith and levers pivoted with the carriers and with the pull bar, handle bars and levers coupled together in a manner to prevent the handle bars and the levers shifting relatively to the pull bar.

A further object of the invention is to provide, in a manner as hereinafter set forth, a seesaw including a supporting structure, a rocking or teetering structure pivotally supported at superposed points with respect to the upper portion of the supporting structure and means arranged at the pivotal supporting points between said structures to prevent injury to the fingers or hand of a person when grasping the seesaw at the points referred to.

A further object of the invention is to provide, in a manner as hereinafter set forth, a seesaw including a rocking or teetering structure, a pair of seat carriers, and a pair of pivotal connections between each carrier and an end of said structure.

A further object of the invention is to provide, in a manner as hereinafter set forth, a seesaw including a rocking or teetering structure, a supporting structure having said other structure arranged over and at each side thereof, and with the rocking structure pivoted centrally of the top and at each side of the supporting structure below the upper end of the latter for increasing the strength and durability of the connection between said structures thereby insuring a maximum amount of safety during rocking or teetering.

A further object of the invention is to provide, a seesaw, in a manner as hereinafter set forth, including seat structures, a rocking or teetering structure carrying and connected with the seat structures, a supporting structure for and suspending the rocking or teetering structure and means for increasing the strength and durability of the parts at the points of connection between the seat structures and rocking or teetering structure and between the latter and the supporting structure.

Further objects of the invention are to provide, in a manner as hereinafter set forth, a seesaw which is strong, durable, compact, readily assembled and disassembled as desired, portable, enjoyable and free of danger when used, capable when rocking or teetering to have its seat structures elevated to a materially greater height than the supporting structure for the rocking or teetering structure, permitting for the expeditious substitute of a non-impaired element for an impaired element when occasion requires and without the necessity of discarding the entire device, comparatively inexpensive to manufacture, and having a free non-retarded rocking or teetering motion.

To the above ends essentially, and to others which may hereinafter be set forth, the invention consists of such parts, and such combination of parts which fall within the scope of the invention as claimed.

In the drawings:

Figure 1 is a side elevation of the seesaw showing the two positions of the rocking or teetering structure in full and in dotted lines.

Figure 2 is a top plan view of the seesaw.

Figure 3 is a fragmentary view in vertical section of the seat structure.

Figure 4 is a sectional detail.

Figure 5 is a fragmentary view in vertical section of the central portion of the seesaw.

Figure 6 is a section on line 6—6 Figure 5.

Figures 7, 8 and 9 are perspective views illustrating several of the elements employed to form the lower central combined bearing, coupling and 10 pivot structure for the rocking or teetering structure.

Figure 10 is a section on line 10—10 Figure 1.

Figure 11 is a fragmentary view in section illustrating the reinforcement for the ends of the 15 lower bars of the rocking or teetering structure.

Figure 12 is a side elevation of the body portion of a seat carrier.

Figure 13 is an inverted perspective view of the seat.

20 Figure 14 is a disassembled view in perspective of the combined coupling bearing and pivot structure between a seat structure and rocking or teetering structure.

Figure 15 is a sectional elevation showing a 25 modified form of seat structure.

The seesaw includes a supporting structure 15, a rockable or teetering structure 16 hereinafter termed a teetering structure, a pair of seat structures 17, 18, a pair of combined lower end bearing, coupling and pivot structures 19, 20 for the structure 16 with respect to the structures 17, 18, an upper central combined bearing, coupling and pivot structure 21 for the structure 16 with respect to the structure 15, a lower central combined bearing, coupling and pivot structure 22 for the structure 16 with respect to the structure 15, and a pair of combined upper end bearing, coupling and pivot structures 23, 24 for the structure 16 with respect to the structures 17, 18.

40 The supporting structure 15 (Figures 1, 5 and 6) is of skeleton form and includes a pair of spaced parallel bars 25 standing on their lower lengthwise extending edges, a combined coupling and supporting bar 26 of greater height than the bars 25, disposed at right angles to the latter, standing on its lower lengthwise extending edge and positioned in aligning notches 27 formed in the top edges of the bars 25 at the transverse medians of the latter. The bars 25 overlap the bar 26. The bars 25, 26 are detachably connected together at their vertical medians. The bar 26 is of greater thickness than either of the bars 25. Positioned at the center of each side of bar 26 is the lower portion of an upright. The uprights are arranged in parallel spaced relation, designated 28, depend slightly below bar 26 and are anchored to the latter by the holdfast devices 29. Each upright 28 is formed in proximity to its upper end with a transverse opening 30. The openings 30 of the uprights 28 align with each other. Each upright is also provided at a point between its transverse median and its opening 30 with an opening 31 of greater diameter than the opening 30. The openings 30 and 31 in each upright also align with the openings. The openings 31 in the uprights align with each other. The upper edges 32 of the uprights are rounded.

70 The teetering structure 16 (Figures 1, 2, 3 and 11) includes a pair of opposed spaced lower slightly bow-shaped oblong members or bars 34 of the desired length, width and thickness and of like form. The members 34 are preferably formed of wood, are oppositely disposed with respect to each other and each is formed with a central opening 75 35 and an opening in proximity to each end there-

of as indicated at 36. The members 34 are positioned on their lower lengthwise extending edges. The openings 35, 36 of one member align with the openings 35, 36 in the other member. The uprights 28 extend upwardly between the members 34 centrally with respect to the latter. The openings 35 of the members 34 align with the openings 31 in the upright 28. The structure 16 also includes an upper member 37 in the form of a bar disposed in spaced alignment with respect to the center of the space formed between the members 34. The member 37 is of slightly less length than either of and coupled with the members 34 in a manner as hereinafter referred to. The means coupling the members 34 and 35 also couples the seat structures with the said members and forms a part of the teetering structure. Each member 34 in proximity to its openings 36 and inwardly with respect to the latter is formed with vertically disposed reinforcing means as indicated at 38, Figure 11. The ends of the members 34 are rounded as at 39. The reinforcing means is in the form of a metal rod upset at each end. The member 37 is preferably formed of wood.

With reference to Figures 1, 2, 3, 12 and 13, each of the seat structures includes a seat carrier 40 formed of an outer rectangular part 41 and an enlarged inner part 42. The bottom edge of the latter forms a continuation of the bottom edge of the former. The inner edge 43 of portion 42 is of convex curvature. The part 42 extends beyond the top edge 44 of part 41. The top edge 45 of part 42 is of ogee curvature. The carrier 40 is disposed upon its lower lengthwise edge and is of the desired thickness and height. The part 41 intermediate its ends is formed with a vertically disposed opening 46. The part 42 rearwardly of its vertical center and below its longitudinal center is formed with transverse openings 47 and 48 above and aligning with the latter with an opening 48 of less diameter than the opening 47. Each side of part 42 is formed with a vertical groove 49 extending from the bottom to the top edge of said part. The outer ends of the openings 47, 48 are intersected centrally by the longitudinal medians of the inner walls of the grooves 49. Terminating at its lower end in the top of the wall of opening 47 is a lubricant conducting channel 50 disposed centrally and lengthwise of the inner wall of one of the grooves 49. The upper end of channel 50 is closed and spaced from opening 48.

Each seat structure also includes a seat member 51 formed of an enlarged outer part 52 and a narrow inner part 53 formed intermediate its ends with an opening 54. The inner end portion of the lower face of part 53 is formed with a groove 55 opening at the inner end 56 of member 51. The top wall of groove 55 is upon a curve, as at 57 extending upwardly in a direction towards said end 56. The width of groove 55 corresponds to the thickness of the carrier 40. The member 51 is seated upon the top edge of carrier 40 with the opening 54 registering with opening 46 and the top wall of groove 55 bearing against a portion of the upper edge of part 42 of the carrier. The groove 55 provides for the inner end portion of part 53 of member 51 to overlap a portion of part 42 of the carrier. Extending through the registering openings 46, 54 is a holdfast means 58 for anchoring the carrier and seat member together. The side walls of groove 55 prevents the lateral shifting of member 51 relative to the carrier.

Each of the combined bearing, coupling and

5 pivot structures 19, 20 (Figures 1, 3 and 10) includes a pair of flat vertical links 58', 58'' which are seated in the grooves 49, flush at their lower ends with the bottom edge and of a length to extend upwardly above the part 42 of a carrier. Each link is formed with openings 59, 59' and 59''. The latter is of greater diameter than the other openings in the link and has the inner end thereof flush with the wall of opening 47 of the carrier.

10 The openings 59' of the links register with the opening 48 of the carrier. A holdfast means 60 extends through the registering openings 48, 59' for securing the links to the carrier. The pivot structure 19 or 20 also includes a bolt 60' having a head 61 at one end and peripheral threads 61' at its other end. A fixed coupling sleeve 62 is mounted in the opening 47 of the carrier and in the openings 59'' of the links. Each opening 59'' is tapered. The openings 59'' are oppositely disposed with respect to each other. The sleeve 62 has its ends expanded, as at 63 to bind against the walls of the openings 59'' whereby the sleeve is anchored to the links and acts as additional securing means between the links and the carrier.

15 The sleeve 62 in proximity to one end thereof is provided with a port 63' which establishes communication between the channel 50 and the interior of sleeve 62. Loosely mounted within the latter and extended from each of the links is a bearing sleeve 64 having its ends abutting a pair of spacing washers 65 positioned against the inner face of the members 34. The bolt 60' extends through the openings 36 at one end of the members 34, the washers 65 and the bearing sleeve 64. Mounted on the bolt 60' and interposed between the head of the latter and a member 34 is a spacing washer 66. The bolt 60' extends beyond one of said members 34 and carries a nut 67 which in connection with the head 61 couples a pivot structure 19 or 20 relative to a seat structure and one end of the teetering structure. Interposed between the said one of said members 34 and the nut 67 is a spacing washer 68.

20 The link 58' is formed with an opening 69 which communicates with the channel 50. The latter in connection with port 63' and opening 69 provides for supplying lubricant to between the sleeves 62, 64. The sleeve 64 provides a bearing for the bolt 60', the latter constituting a pivot. The sleeve 64 also provides a bearing for sleeve 62. The carrier pivots upon sleeve 64.

25 The upper central combined bracing, coupling and pivot structure 21 (Figures 5 and 10) for the teetering structure 15 includes a substantially T-shaped casting 79 having its head 71 formed with a pair of spaced parallel vertical openings 72 and its stem 73 provided with a horizontally disposed opening 74 of greater diameter than either of the openings 72. The head 72 is of rectangular contour and is provided in its upper face with a lengthwise disposed groove 75 extending from one end to the other thereof and has mounted therein the central portion 76 of the bar 37. Positioned in the opening 74 is a bearing sleeve 77 having its ends flush with the sides of casting 79. Extending through the openings 30 and bushing 77 is a bolt 78 having its head 79 abutting the outer side of one of the uprights 28. The bolt 78 extends beyond the other of said uprights 28 and carries a securing nut 80 and mounted on bolt 78 is a spacing washer 81 which is interposed between the other of said uprights 28 and the nut 80. Positioned between casting 79 and the uprights 28 and mounted on bolt 78 are spacing washers 82. Extending through spaced parallel

30 openings 83 formed in the central portion 76 of bar 37 are headed bolts 84 which also extend through the openings 72, as well as depend from the head 71 of casting 79. The lower ends of the bolts 84 carry securing nuts 85. The casting 79 is arranged between and extends above the upper ends of the uprights 28. The stem 73 of casting 79 has a port 86 extending from one side edge of the casting to opening 74 for the purpose of supplying lubricant to the sleeve 77. The bolt 78 and nut 80 couple the bar 37 to the supporting structure 15 and provide a stationary pivot for the teetering structure 16. The head 71 of the casting 79 and bolts 84 act as a bracing and reinforcing means for the central portion 76 of bar 37.

35 The lower central combined bearing, coupling and pivot structure (Figures 5 to 9) for the teetering structure 15 includes bearing sleeve 87 which is mounted in the openings 31 and is of a length to extend from each of the uprights 28. Positioned in and extending from each end of the sleeve 87 is a bearing sleeve 88. Extending through the openings 35 in the members 34 and through the sleeve 88 is a headed bolt 89 which abuts the outer side face of one of the members 34 and extends from the outer side face of the other member 34. The bolt 89 carries a securing nut 90. A pair of spacing washers 91 are mounted on bolt 89 and one is interposed between the nut 90 and one of the members 34 and the other is interposed between the head 92 of the bolt and the end of said members 34. A pair of spacing washers 93 are mounted on the bolt 89 and are interposed between the outer ends of sleeve 88 and the members 34. The bolt 89 and nut 90 couple the teetering structure 16 to the supporting structure 15. The bolt 89 provides a movable pivot for the teetering structure 16. The sleeve 87 is formed with an opening 94 for the passage of a lubricant to sleeve 88. The latter has its ends abut the spacing washers 93 and bodily moves with the bolt 89.

40 The combined upper end bearing, coupling and pivot structure 23 or 24 (Figures 1, 3 and 10) for the teetering structure 16 which forms a part of the latter, includes an angle shaped lever or casting 95 formed of a vertical leg 96 and a horizontal leg 97 of greater length than and extends inwardly from the upper end of leg 96. The lower end of the latter is formed with a horizontal opening 98. The upper face of leg 97 is formed with a groove 99 disposed lengthwise of and extending from one end to the other end thereof. The leg 97 is of rectangular contour in plan and is provided intermediate its ends with a vertical opening 100. The leg 96 is arranged between and extends above the upper ends of the links 58', 58''. The opening 98 is of greater diameter than and aligns with the openings 59 in the links 58', 58''. Mounted in the opening 98 is a fixed pivot member 101 having reduced end portions 102 positioned in the openings 59. The outer terminus of each end portion 102 is upset to abut the outer face of a link 58', or 58'' whereby the member 101 is anchored to the links. The bar 37 seats in the groove 99 and is secured to casting 95 by a headed bolt 103 extending downwardly through opening 100. The lower end of bolt 103 carries a securing nut 104.

45 The bar 37 adjacent each end is transversely grooved in its top as at 105 and seated in such groove is a transversely disposed handle member 106 formed with a vertical opening 107 terminating at its upper end into a countersunk portion 108. The bolt 103 and nut 104 also function to

secure the handle member 106 to bar 37. The bolt 103 extends through opening 107 and has its head seated in portion 108.

The modified form of seat structure shown in Figure 15 comprises an oblong carrier 109 formed with a vertical opening 110 between its vertical median and outer end, and a transverse opening 111 between its vertical median and inner end. The opening 111 is arranged below the longitudinal median of the carrier 109. The latter is formed with a vertical channel 112 extended from the upper edge of the carrier 109 to the opening 111. Extending upwardly from the top edge of the carrier 109 between the opening 110 and the outer end of the carrier is a holding pin or lug 113. The carrier 109 at each side thereof is formed with a vertical groove 114, only one shown, and corresponding to grooves 49. The opening 111 communicates with each of the grooves 114. The carrier 109 is provided with a transverse opening 115 adjacent the channel 112 and above opening 111 and which communicates with the grooves 114. Mounted on the top edge of the carrier 109 is a seat member 116 having a socket 117 on its lower face to receive the pin or lug 113 to arrest the shifting of member 116 relative to carrier 109. The seat member 116 is formed with an opening 117 registering with vertical opening 110. Holdfast means 118 secure the carrier 109 and member 116 together and which extend through the openings 116, 117. The grooves 110 correspond to grooves 49, but the inner wall of one of the grooves 114 is not formed with a channel 50 as is provided in carrier 40. The grooves 114 receive a pair of links 118, only one of which is shown. Each link 118 is of a form similar to link 58'. The pivot structure between the modified form of seat structure and the teetering structure 16 is the same as that referred to with respect to a seat structure 19 or 20 with this exception, that both links are substantially similar to link 58' and not provided with an opening 69. The channel 112 permits of the supplying lubricant to the pivot structure between the modified form of seat structure and the teetering structure 16.

The pivot structures 19 or 20 are capable of being disassembled and are so formed that each can be released to enable the substituting of a new bearing sleeve 64 for a worn one without completely removing such structure from a seat or teetering structure and the setting up of such pivot structure with a bearing sleeve 64 reduced to a minimum wear upon the bolt 60'. The foregoing statement applies also to the lower central pivot structure between the supporting and teetering structures. The manner of setting up the lower central pivot structure and the pivot structure 19 or 20 prevents pinching or clamping the hand of a person when grasping the seesaw centrally of and at the ends of the lower portion of the teetering structure. The connections between the seat structures and with the ends of the teetering structure provides for the seat members to be permanently disposed in parallel relation to the ground or other surface upon which the supporting structure is mounted.

The seesaw may be readily knocked down and set up when desired, as the seat structures are detachably connected with the teetering structure and the members 34 of the teetering structure detachably connected with the supporting structure and with the bar 37.

What I claim is:—

1. A seesaw comprising a skeleton teetering

structure including a top part and a bottom part and having a pivot means at each end of its top part and a pivot means at each end of its bottom part, said pivot means for the lower part extending therethrough, carriers within and extending from each end of said bottom part and encompassing the pivot means near each end of said bottom part, means encompassing the pivot means at the ends of said bottom part, secured to the sides of each of said carriers, extending upwardly beyond said sides and encompassing the pivot means near the ends of said top part for connecting said top part with the carriers and with the ends of said bottom part, a vertical supporting structure extending through said bottom part and having its upper end opposing in spaced relation the bottom of said top part, means secured to said top part and anchored to said supporting structure for pivotally supporting said top part at its transverse center over the upper end of said structure, and means anchored to said bottom part and extending through said supporting structure for pivotally supporting said bottom part at its transverse center adjacent opposite sides of said supporting structure below the means for pivotally supporting said top part at the transverse center of the latter.

2. In a seesaw of that type including a vertical supporting structure, a teetering structure opposing in spaced relation the sides and top of and provided at its transverse center with an upper and a lower pivot means for connecting it at its transverse center at two superposed spaced points with the supporting structure, said upper pivot means including a T-shaped casting fixed to the teetering structure and extending into the upper end of the supporting structure, a bearing sleeve mounted in the casting, a pivot bolt extending through the sleeve and supporting structure, a securing nut on the bolt and spacing means for the casting and nut; and said lower pivot means including a sleeve extending through the supporting structure, a bearing sleeve of greater length than, extending through and projecting from the ends of said other sleeve, a pivot bolt extending through the teetering structure and said bearing sleeve, a securing nut on the bolt and spacing means between the bearing sleeve and said structure.

3. A seesaw comprising a vertical supporting structure, a bar arranged above and having means depending centrally therefrom into the top of said structure, said means being pivotally supported in said structure below the top of the latter, a pair of elongated members arranged below said bar and opposing the sides of said structure, means extending through said members and structure for pivotally supporting said members centrally thereof from said structure below the top of the latter, a pair of seat elements arranged between the ends of and extending outwardly from said members, means extending through said members and structure for pivotally supporting the inner ends of said elements from the ends of said members, a pair of links countersunk in, anchored to and extended upwardly from the sides of each of said elements, said links at their lower ends encompassing said means at the ends of said members, apertured members depending from the ends of said bar between the pairs of links, and means for pivotally connecting the upper ends of said links to the said apertured members.

4. A seesaw comprising a vertical supporting

structure, a bar arranged above and having means depending centrally therefrom into the top of said structure, said means being pivotally supported in said structure below the top of the latter, a pair of elongated members arranged below said bar and opposing the sides of said structure, means extending through said members and structure for pivotally supporting said members centrally thereof from said structure below the top of the latter, a pair of seat elements arranged between the ends of and extending outwardly from said members, means extending through said members and elements for pivotally supporting the inner ends of said elements from the ends of said members, a pair of links countersunk in, anchored to and extended upwardly from the sides of each of said elements, said links at their lower ends encompassing said means at the ends of said members, apertured members depending from the ends of said bar between the pairs of links, means for pivotally connecting the upper ends of said links to the said apertured members, and the said means for pivotally supporting the inner ends of said elements, one of the links of each pair of links and said elements having coacting portions for conducting lubricant to the interior of such means.

5. In a seesaw, a teetering structure, a support extending upwardly through said teetering structure, a sleeve anchored to and extending through said support and formed with a lubricant port, a bearing sleeve of greater length than, mounted in and extending from the ends of the other of said sleeves, a headed bolt extending through said bearing sleeve and structure, a securing nut on the bolt, and spacing means on the bolt located between respectively said structure and the ends of the bearing sleeve, said structure and the bolt head and said structure and the nut.

40 6. In a seesaw, a teetering structure including a centrally disposed top bar, a vertical support having its upper end arranged in spaced relation with respect to the bottom of said bar, a casting depending into the top of said support, said casting having its upper end grooved, said bar seating in said groove, means for anchoring the casting to said bar, said casting being formed in proximity to its lower end with an opening, a sleeve positioned in the opening, a headed pivot bolt 45 extending through said support below the top of the latter and through said sleeve, a securing nut on the bolt, and spacing means on the bolt and disposed between the ends of the sleeve and said support.

55 7. In a seesaw, a teetering structure, a support

for the latter, said structure including a top part and a lower part pivotally connected with said support, carriers arranged within and extending from the ends of said low part, pivot means in proximity to the ends of and extending through said lower part for the inner ends of the carriers, seat elements secured upon the carriers, said elements and carriers having coacting means to prevent said elements shifting relative to the carriers, a pair of links secured to and extending above the sides of each of the carriers, castings anchored to the ends of and depending from the bottom of said top part between the links of said pairs, and means for pivotally connecting the upper end of a pair of links to each of said castings.

8. In a seesaw a pair of spaced parallel supporting standards, an upper pivot bolt extending through said standards in proximity to their upper ends, spaced upper spacer elements upon said bolt and abutting the inner face of said standards, a lower pivot bolt extending through and projecting from the outer sides of said standards, said lower pivot bolt having a head at one end and carrying a nut at its upper end and arranged in spaced alignment to said other bolt, a teetering structure formed of a high part and a low part, said high part arranged over said standard and provided with means depending from its lower face to between said upper spacing elements and pivotally mounted on said upper bolt, said lower part formed of two sections, each mounted upon a part of the lower bolt extended from the outer side of a standard in proximity to said head or bolt, a bearing sleeve encompassing said lower bolt and projecting from the outer sides of said standards, a pair of lower spacer elements interposed between the ends of said sleeve and the inner faces of said sections and mounted on said lower bolt, a pair of end bolts constituting pivots, each end bolt extending through said sections near an end thereof, a pair of seat structures extending between the ends of said sections and each including a tubular bearing extending from its sides and mounted upon an end bolt, two pair of upstanding links, each pair being mounted upon an end bolt, anchored to the sides of and extending above a seat structure, spacing means mounted on the end bolts and interposed between the ends of said tubular bearings and the inner faces of said sections, and means for pivotally connecting each pair of links with an end of said high part, the latter being disposed centrally with respect to said low part.

ETHAN HEINLY. 55
